INSTANTANEOUS CIGARETTE
EXTINGUISHER

Victor T. Milward, Santa Barbara, Calif.

Application October 28, 1938, Serial No. 237,535

1 Claim. (Cl. 131—235)

The present invention relates to extinguishers for cigarettes and the like, and has for the primary object the provision of means that may be incorporated into an ash receptacle or detachable therefrom, whereby lighted cigarettes and the like can be extinguished by cutting through the smoldering end thereof.

A further object of the invention is to provide an extinguisher for cigarettes and the like including a hollow tube-like member of metal or other suitable material which has mounted therein or forming a part thereof a vertically disposed blade against which the smoldering end of a cigarette or the like is pressed for extinguishing the same.

The invention will be fully and comprehensively understood from a consideration of the following detailed description when read in connection with the accompanying drawing which forms a part of the application.

In the drawing:

Figure 1 is a perspective view of an ash receptacle having incorporated therein an extinguisher devised according to the present invention;

Figure 2 is a fragmentary sectional view taken substantially on line 2—2 of Figure 1;

Figure 3 is a fragmentary vertical sectional view taken substantially on line 3—3 of Figure 2;

Figure 4 is a top elevational view of a modified form of an extinguishing tube;

Figure 5 is a longitudinal sectional view taken substantially on line 5—5 of Figure 4;

Figure 6 is a side elevational view of a further modified form of the device;

Figure 7 is a vertical sectional view taken substantially on line 7—7 of Figure 6, and

Figure 8 is a side elevational view of one of the extinguisher tubes as used with a novelty.

It is a well known fact that a lighted cigarette, if placed in a horizontal or inclined position will be entirely consumed. It also produces a large volume of offensive smoke while remaining in this position and if special care is not taken to extinguish the cigarette a piece of furniture or the like is often burned in spots and occasionally fires are started.

The present invention is designed to overcome the above objections and, there is broadly provided a hollow tube-like member which may be incorporated into an ash receptacle or it may be readily detachable therefrom. A vertically disposed blade is positioned within the tube and when a cigarette or the like is pressed into

the tube, it encounters the blade and the smoldering end of the cigarette is cut in half and will be discharged through the tube and into the container below.

5 Referring to the drawing for a more detailed description thereof, and particularly Figures 1, 2 and 3, there is disclosed an ash receptacle 10 which may be formed of any desired material and of any shape or size. The ash receptacle 10 is disclosed for purposes of illustration only and it is to be understood that the extinguishing tube forming the essence of the invention may be used with any desired type of ash receptacle. It is preferred, however, that said receptacle, in 10 the process of manufacture, be formed with one or more chambers 11, in which is molded or otherwise secured a hollow cylindrical tube 12. The upper end of the tube is formed with a flange 13 to guide the cigarette or the like to be 15 extinguished therein. The cutting blade 14 is disposed substantially centrally of the tube 11 and extends vertically therein and is preferably fixedly secured to the bottom wall 15 of the receptacle 10 during the manufacture thereof. 20 Referring to Figure 3 of the drawing, it will be noted that the bottom portion of the blade 14 has been formed with transversely extending ears 16 which extend beyond the side walls of the chamber 11 thereby assuring permanent attachment of said blade 14.

In use, the smoldering end of a cigarette or the like is inserted within the tube 12 and is guided by the flange 13, and upon contact with the blade 14, the smoldering end will be cut in 25 half and fall within the receptacle. Cutting through the smoldering end of the cigarette will immediately extinguish the same thereby preventing continuing offensive smoking of the cigarette and reducing to a minimum the hazard 30 of fire. It is to be understood that one or more chambers may be formed in an ash receptacle to accommodate the hollow tube and cutting blade when required.

The modified form of the invention illustrated 35 in Figure 4 and 5 embodies a hollow cylindrical tube having the cutting blade forming an integral part thereof. It will be noted that the upper end of the tube 17 is formed with a guiding flange 18 and during the manufacture thereof 40 of a side wall is cut throughout a portion of its length as indicated at 19 to form the blade 20. It is preferred that the bottom portion of the blade be substantially coplanar with the bottom edge of the tube 17 whereby it can be readily 45 incorporated in a formed chamber of an ash

receptacle in the manner previously described.

The further modified form of the invention illustrated in Figures 6 and 7 embodies the use of a strip of material 21 having semi-circular ears 22 extending therefrom and adapted to be engaged upon the rim of an ash receptacle. One or a plurality of hollow cylindrical tubes 23 are slotted throughout a portion of their length as indicated at 24 and positioned over the upper edge 25 of the member 21. These tubes are also preferably formed with guide flanges 26 and the smoldering end of a cigarette upon contact with the edge 25 of the member 21 will be cut in half and thereby extinguished. It is also to be understood that one or more of the units including the member 21 and the tubes 23 may be detachably secured to an ash receptacle.

To render the device attractive as an ornament, the cutting blade 27, see Figure 8 of the drawing, may be stamped, cut or molded during the manufacture thereof in the form of a figure or other design and the hollow cylindrical tube 28 is slotted through the greater portion of its length and positioned thereover in substantially the same manner as illustrated and described in connection with Figures 6 and 7. This ornamental extinguisher will be formed with lips 29 for attaching the device to the rim or edge of an ash receptacle.

In all of the forms herein above described, use is made of a hollow tube, which tube is preferably the same diameter on the inside as a cigarette

but sufficiently large to permit the cigarette to slide easily therein. The vertically disposed blade will effectively cut the smoldering end of the cigarette thereby disintegrating it and causing it to be immediately extinguished. The tube being open at both ends according to certain forms of the invention will prevent the collection of ashes therein. In the other forms, however, the interior of the tube is readily accessible for cleaning.

Also it will be understood, of course, by those skilled in the art that variations in the hereinabove described device involving the substitution of substantial equivalents for the devices described are intended to be comprehended within the spirit of the present invention and that the invention is capable of extended application and is not confined to the exact showing of the drawing nor to the precise construction described and, therefore, such changes and modifications may be made therein as do not affect the spirit of the invention nor exceed the scope thereof as expressed in the appended claim.

What is claimed is:

25 A cigarette extinguisher, comprising a hollow tube adapted for association with an ash receptacle, and a blade vertically disposed within said tube and having a horizontal transverse edge approximately midway between the upper and lower end of the tube.

VICTOR T. MILWARD.
